UNITED STATES PATENT OFFICE.

BERNARD D. WILLIS, OF OAK PARK, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed March 29, 1920. Serial No. 369,789.

To all whom it may concern:

Be it known that I, BERNARD D. WILLIS, a citizen of the United States of America, and resident of Oak Park, in the county of 5 Cook, in the State of Illinois, have invented certain new and useful Improvements in Automatic Telephone Systems, of which the following is a specification.

My invention relates in general to automatic telephone systems, but more especially to such automatic systems as include private automatic branch exchanges, commonly known as P. A. X.'s; and the object of the invention is to provide new and improved 10 main to P. A. X. trunk circuits which are well adapted for use in connection with private automatic exchanges of large size.

In accomplishing this object numerous new features have been developed and new 15 circuits designed, resulting in a very efficient system characterized by the absence of all complicated equipment at the attendant operator's positions, and having, nevertheless, all the principal operating features which 20 have heretofore been considered desirable in a system of this kind. All of which will be explained fully in the detailed specification which is to follow, reference being had to the accompanying drawings forming a 25 part thereof.

Referring to the drawings, comprising 30 Figs. 1, 2, and 3, I have shown therein the complete circuits of a main to P. A. X. trunk, including all the apparatus at the 35 private automatic exchange which is necessary in order to complete a connection from a calling subscriber in the main exchange to a called subscriber in the branch exchange. The local switches and circuits in the main 40 exchange have not been shown, as they have nothing in particular to do with the invention. It may be stated, however, that the main exchange may be of any standard two wire type such as is in common use today, 45 and may be of any desired capacity. The branch exchange may be of the same general type as the main exchange although of smaller capacity. As shown herein a branch exchange of 1000 lines capacity is contemplated, although the size may of course be increased or diminished to suit the circumstances of any particular case.

To proceed with the explanation, the 50 trunk line comprising conductors 2 and 3 is one of a group of trunk lines which are ac-

cessible to selector switches in the main exchange and which extend by way of the usual repeaters to so called incoming selectors at the private automatic exchange. There are a number of attendant operators 60 at the branch exchange or P. A. X., whose duty it is to handle general calls directed to the establishment in which the P. A. X. is located; and all of the main to P. A. X. trunks pass through the attendant operator's 65 positions before terminating in the incoming selectors. This is clearly shown in the drawing wherein the trunk line shown in Fig. 1 is connected to multiple jacks J¹, J², and J³, which are located at the first, second, 70 and third operators' positions, respectively, and extends to and terminates in the incoming selector E, Fig. 2.

The incoming selector E is a vertical and rotary switch of the well known Strowger 75 type, as are the other numerical switches in the system, and functions as a first selector to pick out desired groups of connectors in the usual and well known manner. Theoretically, there may be ten such groups of 80 connectors to which the incoming selector E and other similar selectors have access in common with the local first selectors of the P. A. X.; but in actual practice, since the tenth level is used as a general call level for 85 signalling an attendant operator, as will be explained, the actual capacity is only 9 groups, or 900 lines. A connector in one of these groups is indicated by the reference character H, Fig. 3. The connector H is a 90 vertical and rotary switch of the Strowger type and is one of a group of similar connectors which have access to a group of 100 local lines in the P. A. X., one of which lines is the line extending to the substation A. 95 The reference character C' indicates an individual line switch of the rotary type whose function it is to extend the line of substation A when calling to an idle local first selector (not shown).

The attendant operators do not handle all the incoming calls to the private automatic exchange but only those calls which are required to be distributed to the proper local parties. This may be made a little more 105 clear by a consideration of the numbering scheme. Let it be assumed that the private branch exchange is located in a large manufacturing establishment, for example, and we will assume that the main to P. A. 110

X. trunks are accessible from the second level of the second thousand group of second selectors in the main exchange. With this arrangement, access to the main to 5 P. A. X. trunks is had by calling the digit 2 twice, and after connection is established with one of these trunks any subscriber in the P. A. X. can be connected with by calling the digits in the local telephone number. Certain of the local exchange telephones may be given direct incoming service by listing their numbers in the telephone directory, the number 22 being prefixed to the local numbers. For example local station 10 number 345 would be listed in the directory as number 22345. In a great many cases, however, perhaps in a majority of cases, incoming calls will not be directed to any particular stations or individuals but 15 will be directed simply to the company or organization, and are answered by one of the attendant operators, who subsequently switches the calls to the proper stations after ascertaining the wants of the calling parties. To handle this class of calls the tenth 20 level in the incoming selectors, corresponding to the digit 0, is reserved, and when this digit is called on one of the incoming selectors a line signal is lighted in front of 25 an idle attendant operator. It will be evident then that the directory telephone number of the company or establishment which is served by the private automatic exchange will be number 220. It may be stated in 30 this connection that the attendant operators may be reached by local subscribers also by calling the digit 0, there being a number of information trunks terminating in the tenth level of the local first selectors. Such 35 arrangement is not shown in the drawings but is in accordance with standard practice and is mentioned here merely to assist in an understanding of the system as a whole.

40 In order to distribute the general or miscellaneous company calls to idle operators each of the incoming selectors is provided with a rotary line switch which is operated, when the associated selector is raised to the 45 tenth level, to select an idle operator's position and light the line lamp thereat which is associated with the trunk line over which the call has been received. The rotary line switch which is associated with the selector 50 E, Fig. 2, is shown just above the said selector and is indicated by the reference character C.

55 The foregoing general remarks will serve to give a general idea of the purpose and 60 scope of the invention. I will now explain more in detail the operation of the circuits themselves, with the object of pointing out the new improvements and explaining their utility. For this purpose it will be assumed 65 first that a subscriber in the main exchange

desires to call the subscriber at substation A in the private automatic exchange, whose telephone number as listed in the directory is number 22345. After explaining the operations which take place in setting up this 70 type of connection, it will be assumed that a call directed to the company itself is received, and the manner in which this call is handled by an attendant operator and extended to the proper local station will then 75 be explained in detail. To proceed, when the main exchange subscriber removes his receiver his line is extended by means of the usual line switch or trunk selector to an idle first selector switch, which is operated responsive to the calling of the digit 2 to select an idle trunk line leading to an idle second selector in the second thousand group. The selected second selector is then operated responsive to the calling of the second 80 digit 2, to select an idle trunk line leading to the private automatic exchange, and it will be assumed that the trunk line selected is the trunk line comprising conductors 2 and 3, Fig. 1. In accordance with well 85 known practice, the two line conductors of the trunk line coming from the selector banks terminate in the line relay of a repeater which is inserted in the trunk line as previously mentioned. When the trunk line 90 is seized, therefore, the line and release relays of the repeater will be energized and a bridge will be closed across the outgoing trunk conductors, these conductors being the conductors 2 and 3. When this bridge is 95 closed at the repeater a circuit is completed for the double wound line relay 50 of the incoming selector E, and this relay is at once 100 operated to close the circuit of the slow-acting release relay 51. Relay 51, upon energizing, prepares the selector for operation in its vertical movement in the usual manner.

The calling subscriber may now operate his calling device in accordance with the 105 digit 3 which is the next digit in the telephone number. The resulting circuit interruptions are repeated by the line relay of the repeater which interrupts the bridge across trunk line conductors 2 and 3 each 110 time its own circuit is interrupted, and causes the line relay 50 of the incoming selector E to deenergize a corresponding number of times and send a series of current 115 impulses through the slow acting series relay 55 and the vertical magnet 59. Responsive to these impulses the vertical magnet 59 is operated to raise the switch shaft 120 step by step until the wipers 80-83, inclusive, stand opposite the third level of bank contacts. The slow acting relay 55 is energized in series with the vertical magnet, maintaining its armature attracted throughout the vertical movement of the switch, and 125 at the first upward movement of the switch 130

shaft closes an initial energizing circuit for the stepping relay 56. Upon energizing, relay 56 prepares a circuit for the rotary magnet 57 at its lower armature, and at its upper armature establishes a locking circuit for itself. At the end of the vertical movement of the switch the slow acting relay 55 deenergizes and closes the circuit of the rotary magnet 57, which is accordingly operated to rotate the wipers 80—83, inclusive, into engagement with the first set of bank contacts in the level opposite which they were raised, the third level in this case. Near the end of its stroke, the rotary magnet 15 opens the locking circuit of the stepping relay 56 which is deenergized therefore and opens the circuit of the rotary magnet. The rotary magnet then deenergizes also and again closes its interrupter contact. The operation now depends upon whether the trunk line with which the wipers have connected is busy or idle. If this trunk line is busy the test contact associated therewith will have a ground potential upon it and the stepping relay 56 will again be energized by current flow over a path which may be traced as follows: grounded test contact, test wiper 82, armature 67 and its resting contact, interrupter contact of the rotary magnet 57, off normal springs 63, and the winding of the stepping relay 56 to battery. Upon energizing, the stepping relay again closes the circuit of the rotary magnet which operates to rotate the switch wipers into engagement with the next set of bank contacts. This operation will continue as long as the test wiper 82 continues to engage grounded test contacts. When a nongrounded test contact is reached, which we will assume to be the test contact 86 associated with the trunk line comprising conductors 88—91, inclusive, the stepping relay 56 is not again energized, but instead the switching relay 58, which heretofore has been short circuited, is energized by current flow over a circuit which extends as follows: grounded conductor 71, winding of the switching relay 58, interrupter contact of the rotary magnet 57, off normal springs 63, and the winding of the switching relay 56 to battery. Owing to the high resistance of the switching relay 58 relay 56 is not operated. Upon energizing, relay 58 connects the test wiper 82 with the grounded conductor 71 at its armature 67, and at its armatures 66 and 70 disconnects the trunk conductors 2 and 3 from the windings of the line relay 50 and extends them by way of the working contacts of these armatures, line wipers 80 and 83, bank contacts 84 and 87, trunk conductors 88 and 91, and normally closed contacts of the reversing relay 150 to the upper and lower windings of the double wound line relay 151 of the connector H, Fig. 3.

When the trunk line is extended to the connector H as above described, the line relay 151 is energized and closes a circuit for the slow acting release relay 152. Upon energizing in turn relay 152 prepares the connector switch for operation in its vertical movement at its armature 165, and at its armature 166 completes a holding circuit extending back to the selector E over the following path: ground at G², working contact of armature 166, conductor 90, test contact 86, test wiper 82, and armature 67 and its working contact to conductor 71, whence the circuit extends as previously traced through the windings of the switching relay 58 and the stepping relay 56 in series to battery. By retaining its armature 68 in operated position the switching relay serves to prevent the release of the selector switch after the relays 50 and 51 have deenergized. The holding circuit just described also serves to maintain ground potential on the multiples of test contact 86 in the banks of the other selector switches in order to make the trunk line extending to connector H busy.

The calling subscriber may now operate his calling device in accordance with the next digit in the desired number, with the result that a series of interruptions is produced in the bridge across trunk conductors 2 and 3 as before, thereby causing a series of deenergizations of the line relay 151 of the connector H. At each deenergization the line relay transmits a current impulse to the vertical magnet 159 over the following circuit: ground at G⁴, armature 164 and its resting contact, armature 165 and its working contact, off normal springs 161 and 163, winding of the slow acting series relay 153, and the winding of the vertical magnet 159 to battery. The above is the circuit over which the first impulse is transmitted. At the first upward movement of the shaft the off normal springs are shifted and the circuit is completed over a new path as follows: armature 165 and its working contact, off normal springs 161 and 162, armature 167 and its working contact (relay 153 being now energized), winding of relay 153, and the winding of the vertical magnet 159 to battery. By the operation of the vertical magnet the wipers 190—192, inclusive, are raised step by step until they stand opposite the level of bank contacts in which is located the contacts associated with the line of substation A. The slow acting relay 153, which is energized in series with the vertical magnet, maintains its armature attracted during the vertical operation of the switch, and at the end of the vertical movement deenergizes and transfers the operating circuit from the vertical magnet 159 to the rotary magnet 158.

The calling subscriber may now operate his calling device in accordance with the next and final digit in the desired number.

As before, a series of interruptions is produced at the repeater in the bridge across the trunk conductors 2 and 3, and the line relay 151 is again deenergized a number 5 of times, transmitting impulses to the rotary magnet 158 over the following circuit: ground at G⁴, armature 164 and its resting contact, armature 165 and its working contact, off normal springs 161 and 162, armature 167 and its resting contact, resting contact of armature 171 and the said armature, armature 179 and its resting contact, and the winding of the rotary magnet 158 to battery. Responsive to these impulses the 10 rotary magnet is operated to rotate the switch wipers into engagement with the particular set of bank contacts which is associated with the line of substation A, being the bank contacts indicated in the drawing by reference characters 193—195, inclusive. The slow acting relay 156 is energized in parallel with the rotary magnet and remains in operated position during the rotation of the switch. At its armature 174 15 relay 156 connects the test wiper 191 with the test relay 155, and at its armature 175 relay 156 closes the operating circuit over a path which is independent of the armature 171 controlled by the test relay 155 in order 20 to guard against the possibility of the latter relay being momentarily energized while the test wiper 171 is passing over busy test contacts. Assuming first that the line of substation A is busy when called as above described, when the test wiper 191 comes to rest in engagement with test contact 194, it 25 will find a ground potential thereon and the test relay 155 will be energized. When the slow acting relay 156 deenergizes an instant 30 later, a locking circuit will be established for relay 155 by way of its armature 173 in an obvious manner. In energized position the test relay also opens the rotary magnet circuit at its armature 171 and at 35 its armature 172 connects a lead from the busy signalling machine Q to the lower talking conductor. By this latter operation the calling subscriber is given an audible 40 busy signal, and being advised thereby that the desired line is for the time being inaccessible, he will replace his receiver.

Having described the operations which take place when the called line is busy, it 45 will now be assumed that the called line is idle. Under these circumstances, when the test wiper 191 comes to rest in engagement with test contact 194, it will find no ground potential and the test relay 155 will not be 50 energized. Then when the slow acting relay 156 deenergizes the following circuit will be completed: grounded conductor 90, armature 173 and its resting contact, upper winding of the switching relay 157, resting 55 contact of armature 174 and the said armature, test wiper 191, test contact 194, wind-

ing of the switching relay 196 of line switch C', and the winding of the stepping magnet 197 to battery. Upon the closure of the above circuit relays 157 and 196 are energized in series and the latter relay operates 70 to disconnect the line of substation A from its normal battery and ground connections in the line switch C'. It is noted that the relay 196 is operated only about half way, due to the fact that the line relay of the line switch has not been energized, and the line conductors are not connected through to the line switch wipers. At the connector II when the switching relay 157 is energized 75 it establishes a locking circuit for itself at 80 its armature 178, opens the rotary magnet circuit at its armature 179, connects direct ground to the test wiper 191 at its armature 177, and at its armatures 176 and 180 closes the talking conductors through to the 85 line wipers of the connector.

The connection having been finally completed, ringing current from the generator Gen is projected intermittently out over the line of substation A in the usual manner to 90 operate the bridged ringer at the substation. It will be noticed that the return path for the ringing current includes the upper winding of the ring cut-off relay 154, and when the called subscriber responds by removing his receiver the ring cut-off relay is 95 energized and establishes a locking circuit for itself at its armature 168. The ring cut-off relay also opens the ringing circuit at its armatures 169 and 170, and at the 100 working contacts of these same armatures finally completes the talking circuit. The calling subscriber is supplied with talking battery from the line relay in the repeater at the main exchange in the well known manner, while the called subscriber is supplied with talking battery through the 105 windings of the double wound back bridge relay 150. Relay 150 is energized while the receiver at substation A remains off the hook and reverses the direction of current flow in the incoming trunk conductors 88 and 91. This operation is of no particular 110 utility in connection with the present disclosure, but being a standard operation the 115 circuits are shown in this manner.

Conversation may now proceed over the established connection, which it will be noticed has been set up entirely automatically, 120 and without any assistance from any of the attendant operators whose equipment is shown in Fig. 1. When the conversation is finished both subscribers will replace their receivers. The release of the automatic equipment is brought about by the replacement of the receiver at the calling substation which opens the circuit of the line relay of the repeater at the main exchange. The release relay of the repeater is then 125 deenergized causing the release of the main 130

exchange automatic switches and the opening of the bridge across the trunk conductors 2 and 3. As a result, the line relay 151 of the connector H, Fig. 3, is permanently deenergized followed by the deenergization of the release relay 152. This latter relay closes the circuit of the release magnet 160 and the connector H is restored in the usual manner. Relay 152 also opens the holding circuit extending back to the selector E, whereupon the switching relay 58 is deenergized and the selector is restored to normal through the medium of its release magnet 60.

Although there is nothing especially novel in the operations described in the preceding paragraphs, it has been considered advisable to include them in order to give a clear understanding of the operation of the system in handling strictly automatic connections; and in addition it will enable the rest of the explanation to be given in a more general manner as regards the operation of the switches themselves, thus permitting the explanation to be chiefly directed to the new features of operation. It will be supposed now that a main exchange subscriber is calling the company or establishment which is served by the private branch exchange equipment shown, using for this purpose the general call number 220. When the digits 2 and 2 are called the connection is extended by means of a first selector and a second selector to the repeater which is associated with an idle trunk line, the trunk line comprising conductors 2 and 3, for example, all as previously described. When the next digit is called, which is the digit 0, the wipers of the incoming selector E will be raised to the tenth level, after which the switch will automatically rotate in the usual manner to select an idle set of bank contacts in that level. With each set of bank contacts in the tenth level there is associated a pair of relays, such as relays 92 and 93, which are provided for the purpose of establishing a holding circuit for selectors which are raised to the tenth level. Assuming that the tenth level set of bank contacts shown in the drawing is the first idle set, the wipers of the selector E will come to rest in engagement therewith, the switching relay 58 will be energized, and the line conductors will be extended through to the relay 92. Relay 92 is then energized, followed by the energization of relay 93, which relay establishes a holding circuit for the selector to maintain the same in operated position.

When the shaft of the selector E is raised to the tenth level, the upper set of off normal springs, comprising off normal springs 64 and off normal springs 65, are closed, and by the closure of off normal springs 65 a circuit is completed for the line relay 100 of

the rotary line switch C. Upon energizing, relay 100 closes a circuit at its armature 107 which includes the switching relay 101 and the stepping magnet 102 in series, and at its armatures 106 and 108 closes contacts 70 which connect the test wiper 104 to the above circuit at a point midway between the said relay and the said magnet. The operation now depends upon whether the test contact with which the test wiper 104 is in 75 engagement is grounded or is not grounded, which in turn depends upon whether the operator's position with which such contact is associated is busy or is not busy. It will be assumed that the first two operator's 80 positions are busy, and such being the case, the first two test contacts associated with the test wiper 104 will have a ground potential upon them. It follows that the switching relay 101 will be temporarily 85 short circuited while the stepping magnet 102 is operated to rotate the switch wipers two steps until the test wiper 104 comes into engagement with the third test contact in its banks. Assuming that the third 90 operator's position is idle the third test contact will not be grounded and the rotation of the line switch will cease. The switching relay 101 is now energized and is of such high resistance that the stepping magnet 102 is 95 not affected. Relay 101, upon energizing, connects ground G⁵ to the test wiper 104 as follows: ground at G⁵, armature 107, working contact of armature 109 and the said armature, and armature 108 and its working contact to the test wiper 104. By this means the third test contact in the bank of the test wiper 104 is instantly grounded and the third position is made busy to other switches, it being understood of course that 100 the banks of the line switch C are connected in multiple with the banks of the other line switches. A circuit may now be traced for the line lamp L³ as follows: ground at G⁵, working contact of armature 107 and the 110 said armature, working contact of armature 109 and the said armature, wiper 103, conductor 16, lamp L³, common conductor 13, and the winding of the pilot relay 7 to battery. By current flow in the above circuit 115 the lamp L³ is lighted and indicates to the operator that a call has been received over the trunk line associated therewith. Relay 7 is energized at the same time, lights the 120 pilot lamp L⁴, and also extends ground by way of conductor 10 to the multiple test contacts in the banks of the line switches.

When the operator at position No. 3 observes the lighted lamp L³ she will respond by inserting the plug of her special cord 125 circuit O in the jack J³. By this operation the operator's head set is connected across the trunk line conductors 2 and 3, and at the same time a circuit is completed by way of the sleeve of the jack and the conductor 130

4 which includes the auxiliary line relay 52 of the incoming selector E. The line relay 52 is accordingly energized and closes the following circuit for relay 53: ground at 5 G^a, armature 71 and its working contact, the off normal springs 64, normally closed contacts controlled by armature 72, and the winding of relay 53 to battery. Relay 53 is energized and establishes a locking circuit for itself at its armature 72, at the same time breaking its original energizing circuit. In addition, relay 53 closes a circuit for the release magnet 60 as follows: ground at G^a, armature 71 and its working contact, 10 armature 73 and its working contact, off normal springs 61, and the winding of the release magnet 60 to battery. By the operation of the release magnet the incoming selector E is restored to normal position, 15 and both upper and lower sets of off normal springs are returned to their original positions as shown in the drawing. By the opening of off normal springs 65 the circuit of the line relay 100 of the line switch C 20 is broken and relays 100 and 101 are therefore deenergized. Line switch C is thus restored to its normal condition, the wipers 103 and 104, however, remaining in connection with their respective third bank contacts. The relays 100 and 101 having deenergized, ground is removed from both of 25 the line switch wipers 103 and 104, and the line lamp L^a is extinguished. The pilot relay 7 then deenergizes, extinguishes the pilot lamp L^a, and removes ground from conductor 10 thereby removing the busy condition from the third test contacts in the banks of the line switches, and rendering the third position accessible to other incoming calls.

Returning to the selector E, when the selector is released as before described the locking circuit of relay 53 is broken at off normal springs 62 and the said relay is 40 therefore deenergized. Armature 73 of relay 53 now being in retracted position, a circuit is established for the slow acting relay 54 which, upon energizing, prepares a circuit for the vertical magnet 59, which 45 will be traced shortly. The attendant operator at the No. 3 position, whose cord circuit O has been connected with the trunk line by way of jack J^a, will now inquire of the calling subscriber and ascertain the 50 name of the local party with whom he desires to converse. Assuming that the wanted party is the party at the local station A, the number of which is No. 345, the operator will proceed to call this number by means 55 of her calling device S, which is included in the circuit of the auxiliary line relay 52 of the incoming selector. When the calling device is operated in accordance with the digit 3 the line relay 52 is deenergized three 60 times and at each deenergization transmits

a current impulse to the vertical magnet 59 over the following circuit: ground at G^a, armature 71 and its resting contact, armature 74 and its working contact, armature 69 and its resting contact, winding of the slow acting relay 55, and the winding of the vertical magnet 59 to battery. The vertical magnet 59 is thus operated under control of the line relay 52 to raise the switch shaft step by step until the wipers 80-83, inclusive, stand opposite the third level of bank contacts. At the end of the vertical movement the wipers are automatically rotated in search of an idle trunk line as has been previously described, and it will be assumed that the wipers are brought to rest in engagement with the bank contacts 84-87, inclusive, in which contacts is terminated the trunk line extending to the connector H, Fig. 3. The switching relay 58 is now energized, and at its armature 69 opens the circuit extending to the vertical magnet 59 of the incoming selector.

The operator may now call the next digit in the number, or the digit 4, thereby causing another series of deenergizations of the line relay 52 which now at each deenergization transmits a current impulse to the vertical magnet 159 of the connector H as follows: ground at G^a, armature 71 and its resting contact, armature 74 and its working contact, wiper 81, bank contact 85, conductor 89, off normal springs 161 and 163, winding of the slow acting relay 153, and the winding of the vertical magnet 159 to battery. It will be seen that the above circuit is very similar so far as the wiring in the connector is concerned to the operating circuit described in the previous operation of the connector, the incoming trunk conductor 89 over which the impulses are received being simply tapped on to the regular operating circuit at the contact spring which forms the working contact of armature 165 of the relay 152. The connector is therefore operated in the same manner as was described in the previous case and the wipers are raised opposite the level in which is terminated the line of the desired called station. When the dial of the calling device S is operated in accordance with the last digit in the desired number, another series of impulses is transmitted to the connector H over conductor 89 and the switch wipers are rotated until they come to rest in engagement with bank contacts 193-195, inclusive, thus completing the connection. The remaining operations by which the called subscriber is signalled, and so on, have already been explained and will not need to be referred to again.

It will be observed that when the operator sets up the connection to complete an incoming call, the switches are operated over circuits which are entirely separate from the

talking conductors and no complicated devices are required in order to open the talking circuit while the operator's calling device is being operated to prevent the calling subscriber from hearing the impulses. The operator's head set is bridged across the trunk all the time, and she can call the required number, or start to call, while still talking. Since the incoming trunk line conductors continue without interruptions through the attendant operator's positions the line relay 50 of the selector is always energized whether the operator is engaged in setting up the connection or not, and after 15 the selector E has cut through and extended the connection to a connector switch the line relay of such connector will be energized. It follows that the release of the connection is at all times under the control of the calling subscriber, and after the operator has 20 finished calling the required number she may remove her plug from the jack and give her attention to another call. When the plug is removed from the jack the auxiliary 25 line relay 52 of the incoming selector E is deenergized, but without interfering in any way with the connection which has been established. The line relay 151 at the connector remains in energized position until 30 the calling subscriber hangs up his receiver, when the connection is released in the same manner as was previously described.

In order to enable the operator to release the established connection in case she has 35 accidentally called the wrong number a release key is provided for each incoming trunk at each operator's position. These keys are indicated by the reference characters K¹, K² and K³ in Fig. 1. Assuming 40 that the attendant operator at position No. 3 has established a connection through the medium of the switches shown and desires to release the connection for the purpose of calling another number, the operation is as 45 follows: key K³ is actuated momentarily and closes the following circuit: ground at G¹, contacts of key K³, conductor 16, wiper 103 (normally stands on bank contact last connected with), armature 108 and its rest- 50 ing contact, normally closed contact springs controlled by armature 72, and the winding of relay 53 to battery. Relay 53 is accord- 55 ingly energized, establishes a locking circuit for itself, and closes the circuit of the release magnet 60, all as was previously ex- 60 plained when it was described how the incoming selector was released from the tenth level by the insertion of the plug in the jack J³. The selector having been released 65 the connector H is of course released also, because the connection thereto is broken at the selector wipers, and all the switches are thus restored to normal and may be re- 70 operated to set up a new connection.

Having described my invention, what I

consider to be new and desire to have protected by Letters Patent will be pointed out in the appended claims.

What I claim as my invention is:

1. In a telephone system, an incoming trunk line terminating in a selector switch at a branch exchange, multiple terminals of said trunk line at a plurality of operators' positions, and means associated with said switch and controllable after said switch has been operated for selecting and signaling an idle operator. 75

2. In a telephone system, an incoming trunk line terminating in a selector switch at a branch exchange, multiple terminals of said trunk line at a plurality of operators' positions, an auxiliary switch associated with said selector, and means controlled over said trunk line for operating said auxiliary switch to select and signal an idle operator. 80

3. In a telephone system, an incoming trunk line terminating in a selector switch at a branch exchange, multiple terminals of said trunk line at a plurality of operators' positions, an auxiliary switch for selecting 90 idle operators' positions, lines accessible to said selector switch, and means for operating said selector switch over said trunk line either to select one of said lines or to start 95 said auxiliary switch, at the option of a calling party.

4. In a telephone system, trunk lines extending from a main exchange to a branch exchange and terminating in automatic switches, multiple terminals for each of said 100 trunk lines at a plurality of operators' positions, means controllable by calling main exchange subscribers for connecting with said trunk lines, means for operating said switches under control of said calling sub- 105 scribers or under control of the operators at said positions to extend connections to branch exchange subscribers, and means under the control of the said calling subscribers for testing said operators' positions 110 and for selecting and signaling idle operators.

5. In a telephone system, trunk lines extending from a main exchange to a branch exchange and terminating in automatic 115 switches, multiple terminals for each of said trunk lines at a plurality of operators' positions, means controllable by calling main exchange subscribers for connecting with said trunk lines, means for operating said 120 switches under control of said calling subscribers or under control of the operators at said positions to extend connections to branch exchange subscribers, and an auxiliary switch associated with each of 125 said first named switches, the said auxiliary switches being controllable by the calling subscribers to select and signal idle operators.

6. In a telephone system, trunk lines ex-

tending from a main exchange to a branch exchange and terminating in automatic switches, means whereby calling main exchange subscribers can connect with said 5 trunk lines and operate said switches in setting up main to branch exchange connections, multiple terminals for each of said trunk lines at a plurality of operators' positions, and means associated with each switch 10 responsive to a predetermined operation thereof for automatically selecting and signalling an idle operator.

7. In a telephone system, trunk lines extending from a main exchange to a branch 15 exchange and terminating in automatic switches, means whereby calling main exchange subscribers can connect with said trunk lines and operate said switches in setting up main to branch exchange connections, multiple terminals permanently 20 connected to each of said trunk lines at a plurality of operators' positions, a line signal for each trunk line at each position, and means associated with each switch responsive to a predetermined operation thereof 25 for actuating the line signal at an idle position to notify the operator that a call has been received over the associated trunk.

8. In a telephone system, a trunk line extending from selector banks in an automatic main exchange to an automatic switch in a branch exchange, said trunk line and automatic switch being available for use in establishing main to branch exchange 30 connections, multiple terminals of said trunk line at a plurality of operators' positions, a line signal at each of said positions, an auxiliary switch operable to select an idle one of said positions and operate the signal 35 thereat, and means whereby a calling main exchange subscriber, if he desired to signal an operator, may start the operation of said auxiliary switch by operating the said first switch to a certain predetermined position.

45 9. In a telephone system, a trunk line extending from a main exchange to a branch exchange and terminating in an automatic switch, multiple terminals for said trunk line at a plurality of operators' positions, 50 means whereby a calling main exchange subscriber can seize said trunk line and operate said switch, and means responsive to a certain predetermined operation of said switch for signalling an idle operator, said means comprising a second switch independently operable 55 while said first switch is standing in operated position.

60 10. In a telephone system, a trunk line extending from a main exchange to a branch exchange and terminating in an automatic switch, multiple terminals for said trunk line at a plurality of operators' positions, means whereby a calling main exchange subscriber can seize said trunk line and operate 65 said switch, means responsive to a certain

predetermined operation of said switch for signalling an idle operator, and means for automatically releasing said switch when the operator answers the call, the connection between the subscriber's line and said switch 70 being maintained intact while the switch is being released.

11. In a telephone system, a trunk line extending from a main exchange to a branch exchange and terminating in an automatic 75 switch, multiple terminals for said trunk line at a plurality of operators' positions, means whereby a calling main exchange subscriber can seize said trunk line and operate said switch, a circuit over which said switch is controlled, means responsive to a certain predetermined operation of said switch for signalling an idle operator, means for automatically releasing said switch when the operator answers the call, 80 and a second circuit independent of the circuit used by the subscriber over which the operator can control said switch and reoperate the same to extend the connection in the direction of a called line in the branch 85 exchange.

12. In a telephone system, a trunk line accessible to calling subscribers and terminating in an automatic switch, means for variably operating said switch in accordance 95 with digits in called telephone numbers, a plurality of operators also having access to said trunk line, and means for signalling an idle operator when said switch is operated in accordance with a single particular digit. 100

13. In an automatic telephone system, a selector switch and an auxiliary switch permanently associated, the latter switch having access to lines extending to operators' positions, means for variably operating said 105 selector switch under control of calling subscribers to establish connections, and means responsive to a certain predetermined operation of said selector switch for initiating the operation of said auxiliary switch to 110 select an idle one of said lines.

14. In a telephone system, serially related selector and connector switches for use in setting up a connection between two lines, a motor magnet in the connector switch, and 115 relays in both switches which are operable independently to control said magnet.

15. In a telephone system, a pair of serially related selector and connector switches, means whereby said switches may be used either by subscribers or by operators in establishing connections, a motor magnet in said connector, a relay in said connector for controlling said magnet when the switch is used by a subscriber, and a relay in said selector for controlling said magnet when the switch is used by an operator. 120

16. In a telephone system, a trunk line extending to an automatic connector switch, said switch being for use in establishing two 125

- kinds of connections, a motor magnet in said switch, a circuit for said magnet including the winding thereof and a conductor of said trunk line for operating said magnet for establishing one kind of connection, a relay in said switch, and a second circuit for operating said magnet controlled by said relay for establishing the other kind of connection.
- 10 17. In a telephone system, a trunk line extending to an automatic connector switch, said switch being for use in establishing two kinds of connections, a motor magnet in said switch, a circuit for said magnet including a conductor of said trunk line for operating said magnet for establishing one kind of connection, a relay in said switch, a second circuit for operating said magnet controlled by said relay for establishing the other kind of connection, another switch for completing connection to said trunk line when a connection of either kind is to be established, and a relay in said last switch for controlling said first circuit.
- 25 18. In a telephone system, means including an automatic selector switch for connecting a calling and called line, two line relays in said switch for independently controlling the operation thereof, and means for operating first one relay and then the other to control said switch in establishing a single connection.
- 30 19. In a telephone system, means including an automatic selector switch for connecting a calling and called line, two line relays in said switch for independently controlling the operation thereof, a circuit over which one of said relays is controlled by the subscriber on the calling line to partially extend a connection, and a circuit over which the other relay is controlled by an operator to complete the same connection.
- 35 20. In a telephone system means including an automatic selector switch for connecting a calling and called line, two line relays in said switch for independently controlling the operation thereof, a circuit independent of the talking circuit for controlling one of said relays to operate the said switch, and a circuit for maintaining the
- other relay energized to prevent the release of the switch while it is being operated.
- 40 21. In a telephone system, a selector switch and a trunk line extending thereto, a line relay for controlling the operation of said switch, means for establishing a control circuit for said relay over two conductors of said trunk line in series, a second line relay for controlling the advancing operation of said switch, and means for establishing a control circuit for said second relay over another conductor of said trunk line.
- 45 22. In a telephone system, a selector switch and a trunk line extending thereto, two line relays in said switch each of which is independently operable to control the entire selective movement of said switch, means for closing a circuit for one of said relays when the trunk line is seized, and means for closing a separate circuit for the other of said relays without opening the circuit of the said first relay.
- 50 23. In a telephone system, a selector switch and a trunk line extending thereto, two line relays in said switch each of which is independently operable to control the entire selective movement of said switch, means for closing separate circuits for said relays over conductors of said trunk line, and means for producing current impulses in one circuit to operate said switch while maintaining the other circuit closed to prevent the release thereof.
- 55 24. In an automatic telephone system, a selector switch, a plurality of groups of other switches, a line relay in said selector operable to control the same to select a desired group of said other switches, a second line relay in said switch also operable to control the same to select a desired group of said other switches, automatic means for selecting an idle switch in the selected group in either case, and a circuit over which the selected idle switch may be controlled in its selective movement by said second relay.
- 60 Signed by me at Chicago, Cook County, Illinois, this 25th day of March, 1920.

BERNARD D. WILLIS.
